UNITED STATES PATENT OFFICE

SAMUEL G. SUPPLEE, OF EAST ORANGE, NEW JERSEY.

DESIGN FOR A SURGICAL TRAY.

46,010.

Specification for Design.

Patented June 23, 1914.

Application filed April 23, 1914. Serial No. 833,993. Term of patent 14 years.

To all whom it may concern:

Be it known that I, SAMUEL G. SUPPLEE, a citizen of the United States, residing at East Orange, in the county of Essex and State of New Jersey, have invented a new, original, and ornamental Design for a Surgical Tray, of which the following is a specification, reference being had to the accompanying drawing, forming part thereof.

In the drawing: the figure shown is a perspective view of the new design of tray.

I claim:

The ornamental design for a surgical tray as shown.

SAMUEL G. SUPPLEE.
